Attns.

UNITED STATES PATENT OFFICE.

ROBERT C. DUGAN, OF BELLE PLAINE, IOWA.

BIN-GATE.

SPECIFICATION forming part of Letters Patent No. 779,590, dated January 10, 1905.

Application filed April 4, 1904. Serial No. 201,603.

To all whom it may concern:

Be it known that I, ROBERT C. DUGAN, a citizen of the United States, residing at Belle Plaine, in the county of Benton and State of Iowa, have invented certain new and useful Improvements in Bin-Gates, of which the following is a specification.

The objects of my invention are to provide a bin-gate of simple, durable, and inexpensive construction which can be easily operated and which will obviate the clogging of the gate when opening and shutting it.

A further object is to provide tracks upon which the gate is designed to move which are of such shape and so constructed that there will be no binding of the gate as it is pushed in and drawn out.

My invention consists in certain details in the construction, arrangement, and combination of the various parts of the device whereby the objects contemplated are attained, as hereinafter more fully set forth, pointed out in my claims, and illustrated in the accompanying drawings, in which—

Figure 1 is a side elevation of my bin-gate mounted in the ordinary discharge-pipe. This figure shows in dotted lines the discharge-pipe in various positions. Fig. 2 is a front elevation of the bin-gate, showing the discharge-pipe attached to the bottom of the ordinary bin. Fig. 3 is a vertical sectional view of the discharge-pipe, showing in cross-section the bin-gate and the track upon which it is mounted. Fig. 4 is a vertical sectional view of the discharge-pipe, showing in longitudinal section the bin-gate. Fig. 5 is a plan view of the bin-gate mounted in the discharge-pipe, and Fig. 6 is a detail view of a portion of the bin-gate and showing in section said gate and one of the tracks upon which one side of the gate is mounted.

Referring to the accompanying drawings, I have used the reference-numeral 10 to indicate the lower portion of the bin upon which the bin-gate is designed to be mounted. This may be of any desired form or shape, and it has an opening 11 leading through the bottom of it, adjacent to which my discharge-pipe is mounted.

The reference-numeral 12 indicates a plate 50 which is designed to be attached to the lower portion of the bin 10. Depending from this plate 12, which is in the form of a circular disk having an opening 13 through its central portion, is the upper portion 14 of the discharge-pipe. The upper portion 14 is some distance outside of the circular opening 13 in the center of the plate 12. Depending from the plate 12 and forming the edges of the opening 13 is the track-supporting collar 15, having 55 mounted on its lower portion the tracks 16 and 17, each of which is V-shaped in cross-section. These tracks are so mounted on the outside of the collar and on diametrically opposite sides thereof that the apex of the V is 60 nearest the circular plate 12. The rear ends of the tracks 16 and 17 are attached to the track-supporting collar 15 by the braces 18 and 19, respectively, and they are connected at their forward ends by the brace 20^a, which is outside of the upper portion 14 of the discharge-pipe. These tracks therefore extend through the openings 20 and 21, which are in the front portion of the upper portion 14 of the discharge-pipe. Extending between these openings 20 and 21 is a slot 22, through which the bin-gate is designed to be moved. Slidably mounted on the tracks 16 and 17 is the gate 23, having the handle 24^a at its forward end. This bin-gate is composed of a flat body portion having the V-shaped flanges 24 and 25 at the edges thereof. Said flanges are designed to be slidably mounted on the tracks 16 and 17, respectively, so that the upper portion of the bin-gate will engage the lower portion of 75 the track-supporting collar 15 when at its inner limit of movement and close the lower end of the opening through the collar 15. By drawing the gate 24 outwardly an opening 80 will be provided at the lower end of the collar 15, through which the grain in the bin will be allowed to drop downwardly. Swiveled to the lower end of the upper portion of the discharge-pipe is the lower portion thereof, which I have designated by the numeral 26 and 85 which is preferably made with an elbow in it and is so attached to the upper portion 14 that it can be swung around from one position to 90

another, as shown in Figs. 1 and 2, so that the grain will be allowed to discharge in the desired direction.

The lower portion 26 has a rim 27 extending outwardly from its upper portion. Attached to the upper portion 14 of the discharge-pipe is a series of lugs 28, which has a substantially U-shaped lower portion 29, in which the rim 27 of the lower portion is designed to rest, so that the lower portion 26 will be held against vertical movement relative to the upper portion 14 by these lugs 28, and at the same time, owing to the construction and arrangement of the lugs 28 and the rim 27 when the lower portion is turned to the right or left, the rim 27 will slide in the U-shaped portions 29 of the lugs 28, so that the lower portion is capable of a swivel movement relative to the upper portion. By having the lower portion 26 swiveled to the upper portion 14 the operator can change the position of the outlet of the discharge-pipe to be carried in various directions.

In practical operation, owing to the peculiar construction of the bin-gate and tracks upon which it is mounted, the said gate will be easily operated without any danger of becoming clogged by the grain which is sustained in the bin by said gate as it flows through the discharge-pipe. By this arrangement of tracks and by having the tracks on the outside of the track-supporting collar 15 the grain does not come in contact in any way with the track or the V-shaped projections which support the gate 23 relative to said tracks and the danger of the clogging of the operative parts of the device is obviated.

Having thus described my invention, what I claim, and desire to secure by Letters Patent of the United States therefor, is—

1. In a device of the class described, a track-supporting collar, tracks mounted on said collar, a gate having projections on each edge thereof designed to move longitudinally of said tracks.

2. In a device of the class described, a discharge-pipe having a slot in the front portion of it, a track-supporting collar inside of the discharge-pipe, a gate mounted on said collar and designed to enter the slot in the discharge-pipe, for the purposes stated.

3. In a device of the class described, a discharge-pipe, a track-supporting collar mounted on the inside of the discharge-pipe, tracks on the track-supporting collar, a gate slidingly

mounted on said track and to pass through an opening in the periphery of the discharge-pipe.

4. In a device of the class described, a discharge-pipe, a track-supporting collar mounted on the inside of the discharge-pipe, tracks on the track-supporting collar, a gate having projections at each edge thereof and extending upwardly therefrom designed to slidingly support the bin-gate on said track. 60 65

5. In a device of the class described, the combination of a track-supporting collar, an inverted-V-shaped track mounted adjacent to the lower portion of said collar, a gate having V-shaped projections at each edge thereof mounted on said tracks and capable of longitudinal movement of them, for the purposes stated. 70

6. In a device of the class described, a discharge-pipe having a slot in the periphery thereof, a track-supporting collar mounted inside of said discharge-pipe, an inverted-V-shaped track mounted adjacent to the lower portion of said collar, a gate having V-shaped projections at each edge thereof mounted on 80 said tracks and capable of longitudinal movement of them, for the purposes stated. 75

7. In a device of the class described, a discharge-pipe composed of an upper portion having a slot in the periphery thereof, a lower portion swiveled to the upper portion, a track-supporting collar mounted inside of the upper portion of the discharge-pipe, an inverted-V-shaped track mounted adjacent to the lower portion of said collar, a gate having V-shaped 85 90 projections at each edge thereof mounted on said tracks and capable of longitudinal movement of them, for the purposes stated. 90

8. In a device of the class described, a discharge-pipe composed of an upper portion 95 having a slot in the periphery thereof, a lower portion swiveled to the upper portion, a track-supporting collar mounted inside of the upper portion of the discharge-pipe, tracks mounted on said collar and a gate slidingly mounted 100 on said track.

9. In a device of the class described, a track-supporting collar, tracks mounted on said collar, and a gate slidingly mounted on said track.

ROBERT C. DUGAN.
